UNITED STATES PATENT OFFICE

PETER J. SHRUM, OF MONACA HEIGHTS, PENNSYLVANIA, ASSIGNOR TO PITTSBURGH SCREW AND BOLT CORPORATION, OF PITTSBURGH, PENNSYLVANIA, A CORPORATION OF PENNSYLVANIA

TAPPING HEAD FOR THREADING MACHINES

Application filed April 14, 1926. Serial No. 101,951.

This invention is for an improvement in threading machines, and relates more particularly to an improvement in a tapping head for threading machines for forming an interior thread on pipes, pipe couplers, thread protectors and the like.

Tapping heads for threading machines are in use at the present time wherein there are radially arranged cutters or chasers in the head which can be projected into operable position, or retracted to an inoperable position. The projecting of the chasers to cutting position is generally effected by means of a tapered mandrel cooperating with the inner ends of the chasers. In such constructions as have been heretofore provided, any one chaser or cutter could not be removed from the head without the removal of the plate which retained all of the chasers in place. Difficulty has also been encountered in obtaining the desired range of adjustment for the expanding movement of the cutters.

According to the present invention, it is proposed to provide a tapping head wherein anyone of the several chasers may be removed without disturbing the other chasers or the retaining plate common to all of the chasers. It is also proposed to provide means by which a wide range of adjustments for the cutters may be procured.

A further object of the present invention is to provide in a machine of this kind a structure by means of which the removal of the tapping head from the machine is facilitated.

Inasmuch as threading machines of the type to which the present invention relates are well known in the art, I have illustrated, in the accompanying drawings, only so much of the machine as is necessary for the understanding of my invention. In the drawings:

Figure 1 represents a side elevation of a tapping head in position in a tapping machine, part of the head being shown in section;

Fig. 2 is a fragmentary section on line II-II of Fig. 1, the section being at right angles to that shown in Fig. 1;

Fig. 3 is a horizontal section on line III-III of Fig. 1;

Fig. 4 is a horizontal section through the

lower end of the tapping head, the section being in the plane of line IV-IV of Fig. 1;

Fig. 5 is a vertical section through the lower part of the tapping head in substantially the plane of line V-V of Fig. 4;

Fig. 6 is a view similar to Fig. 4 only a fragment of the head with a slightly modified form of chaser or cutter being shown;

Figs. 7 to 10 inclusive, are side elevations showing four successive positions of the head in the threading operation.

In the drawings, 2 designates a rotary and vertically reciprocable portion of a standard threading machine, and 3 designates the usual control rods at the sides of the machine.

Received within the end of the part 2 is the reduced shank portion 4 of the tapping head which has a stem portion 5 and a head portion 6. The reduced portion 4 may be attached to the part 2 by means of a transverse key 7.

Passing through the stem portion 5 of the cutter head is a transverse opening 8. Communicating with the opening 8 is an axially extending bore 9 which passes from the lower end of the head up through the stem, terminating at the cross passage 8.

In the head portion 6 are a plurality of radially arranged slots 10 which extend from the inner bore 9 out to the periphery of the head. The periphery of the head is of the usual shape, having the clearance grooves therein as ordinarily provided. Received in each one of the radial slots is a cutter or chaser 11 having thread cutting portions 12 on their outer ends.

The inner ends of the chasers terminate in the central bore and each cutter is provided on its inner end with an inclined or tapered heel portion 13. Several cutters 11 are retained in the slots by means of a plate 14 secured to the lower end face of the head. In each of the chasers on the edge thereof adjacent the plate 14 is a short slot 15. A spring

projected pin 16 carried by the plate 14 engages in the slot 15 for preventing the radial removal of the chasers, while permitting a limited radial movement thereof. A pin 16 is provided for each one of the several chasers.

With this arrangement, it is possible to secure the desired radial movement for the cutters and yet confine the cutters against movement beyond a desired range. The arrangement also permits of the removal of any single cutter or chaser without disturbing the remaining chasers. To remove any cutter or chaser, its pin 16 is pulled down until the inner terminal of the pin is entirely withdrawn from the slot 15. When the pin has been so withdrawn, the chaser may be removed radially from the head.

Operable in the central vertical bore 9 of the head is a rod 17 having an expander or mandrel 18 at its lower end. The upper end of the mandrel is screwed into a cross bar 19 in the transverse slot 8 in the stem of the head. The cross bar 19 has reduced terminal portions 20 which are received in an annular groove 21 on the interior of a threaded nut 22. The nut 22 is screwed onto a threaded sleeve 23 slidable on the stem portion 5 of the head. The sleeve 23 has an annularly grooved flange 24 at its upper end.

In the cross bar 19 is a set screw 25 for adjustably holding the mandrel 17 against turning with respect to the cross bar 19. Upon releasing the set screw 25, the mandrel 17 may be turned to raise or lower it with respect to the cross bar by means of its threaded connection with the cross bar, and thereby vary the effective operating position of the mandrel. The nut 22 is provided with spaced-apart holes 22^a at different points thereabout, by means of which access may be had to the set screw 25. By turning the nut 22 on the sleeve 23, the nut 22 may be raised or lowered on the sleeve and thereby raise or lower the cross bar 19, and in this manner, the effective operating position of the mandrel with respect to the tapping head and the sleeve 23 may be adjusted.

Engaged in the annular groove 24^a of the flange 24, are opposed yoke members 26 which are preferably less than a complete semi-circle, so that the terminals of the yokes are spaced apart as best shown in Fig. 3. The yoke members 26 have supporting lugs 27 thereon, which are bolted at 28 to sleeve members 29 slidable on the side rods 3. With the arrangement as herein provided, the yokes 26 may move up and down with the up-and-down movement of the entire tapping head, thereby sliding the sleeve members 29 on the rods 3. At the same time, the yokes can be removed by merely uncoupling the bolts 28 when it is desired to remove the tapping head, so that it becomes unnecessary to remove the sleeves 29 entirely from the rods 3 as has heretofore been the practice in machines of this type. Carried in the flange 24 are a plurality of spring actuated detent members 30, having terminal portions 31 which are yieldably urged into sockets 32 in hardened steel plates 33 in the upper part

of the stem 5. The purpose of these detents will be hereinafter more fully explained.

Arranged on the rods 3 in the usual manner, are lower limit nuts 34 and upper limit nuts 35. These nuts define the limit of travel of the sleeves 29. Since the sleeves 29 are rigidly connected with the yokes 26, which are engaged into grooves 24^a in the sleeve 24, the nuts 34 and 35 limit the up and down movement of the sleeve 23.

The operation of the tapping head may be readily understood by reference to Figs. 7 to 10 inclusive. The operation is not materially different from that now inherent in present types of machines for this purpose. In Figs. 7 to 10, A designates a coupling in the several stages of threading. The blank is placed under the tapping head when the tapping head is in the elevated position shown in Fig. 7. At this time, the vertically slidable mandrel 18 is in its lowermost position, and in this position its tapered face bears against the tapered heels 13 of the chasers 11. This is clearly shown in Fig. 5. The tapered head 18 of the mandrel in this position prevents the chasers from being pushed radially inward. As the tapping head moves down in the usual operation of the machine, the mandrel 18 stays in this position until the blank A has been threaded to the desired depth.

Upon reaching the termination of the threading movement, the sleeves 29 engage the lower limit nuts 34. The parts are then in the position shown in Fig. 8. The chuck 2 with the tapping head continues to move down a slight distance, while the yokes 26 prevent the sleeve 23 from going down with the head. Therefore, as the head continues to move down, the mandrel 17 with its expander 18 remains stationary. The head will continue to move down until the expander 18 is entirely above the heels 13, whereupon the cutters may contract out of thread cutting position. As the tapping head moves down after the sleeve 23 has been stopped from downward movement, the spring projected detents 30 will function to force the terminals 31 into the sockets or recesses 32. This operation of the detents will occur just when the tapping head has reached its lowermost position.

At this time, the part 2 will start to lift, raising the entire tapping head assembly. The detents 30 will function during this upward movement of the head to prevent the sleeve 23 from dropping by its own weight into a position where the expander 18 would again force the cutters out. As the part 2 continues to lift, the sleeves 29 will be brought into engagement with the upper limit nuts 35. This will prevent the further upward movement of the sleeve 23, but the tapping head will continue to move upwardly a slight distance, thereby forcing the yieldable de-

tents 30 out of holding position. At the same time, the relative upward movement of the stem 5 with respect to the sleeve 23 will cause a corresponding relative movement between the then stationary expander 18 and the upwardly moving cutters. This relative movement will continue until the expander 18 has again forced the chasers out and is in the position shown in Fig. 5. This is also the 10 position of the parts in Fig. 7.

When the chasers have been forced out again and the mandrel is set to hold them from retracting, the movement of the part 2 will be reversed and the next threading operation can be proceeded with.

By reason of the arrangement herein provided, a very delicate adjustment of the mandrel with respect to the cutters can be readily effected. One adjustment is obtainable by releasing the set screw 25 and screwing the threaded upper end of the mandrel 7 up or down in the cross bar 19. A second adjustment can be obtained by screwing the nut 22 up or down on the threaded sleeve 23. 25 By the combination of these two adjustments, quite a wide variation is obtainable and the adjustment can be very accurately made.

In the modification shown in Fig. 6, the chasers are so made as to provide for still another adjustment. In this figure, 6^a designates the head of the threader which has radial slots therein as hereinbefore described. The chasers are made of an outer part 11^a and an inner part or filler 11^b. The two parts have interlocking end terminals as indicated at 11^c. This interlocking connection between the portions 11^a and 11^b prevents any relative radial movement between the two parts. At any time that it is so desired, the part 11^b can be removed by removing the entire chaser from its slot and substituting a similar member therefor, which may be either longer or shorter.

By inserting a longer member 11^b, the 45 diameter of the threader is increased, while the substitution of a shorter member 11^b would permit the cutters to retract to a greater extent. The parts 11^b can be made up in sets which are very closely graduated 50 to obtain close adjustment of the several cutters. With this arrangement, it is also possible to substitute longer or shorter chaser members 11^a, while retaining the same fillers 11^b. It is also possible to replace a worn or 55 broken section 11^a without necessitating the loss of the part 11^b. It is proposed that these cutters will be retained in place by spring pins similar to the spring pins 16 previously described. These pins are shown in Fig. 6 at 16^a.

The tapping head as herein disclosed has several advantages by reason of the fact that the chasers or cutters may be individually removed or replaced without disturbing the 65 plate 14 which holds all of the chasers in the

tapping head. Further advantages arise from the two part construction of the chasers as shown in Fig. 6.

Further important advantages secured by the present invention reside in the threaded connection between the cross bar 19 and the upper end of the mandrel 17, and the provision of the vertically adjustable nut 22 having an annular groove therein for the reception of ends 20 of the cross bar 19.

Still another important advantage of the present invention is the arrangement of the yoke members 26 so that they extend around the flange 24 less than 180° and wherein these yokes are detachably connected with the sliders 29 so that the tapping head may be removed from the machine merely by removal of the nut 7, and disconnecting the bolts 28 without necessitating the removal of the sliders 29 or the rods 3.

I claim:

1. A tapping head for threading machines including a head member having a shank portion, a plurality of chasers carried by the head member, a mandrel for expanding the chasers, a sleeve slidable on the shank, a cross member passing through the shank, and a nut having an annular groove therein threaded on said sleeve, said mandrel being threadedly connected to the cross member, said cross member having reduced end portions adapted to engage and cooperate with the annular groove in said nut.

2. A tapping head for threading machines having a head portion and a shank portion, a plurality of expandable chasers in the head member, a vertically reciprocable element for expanding the chasers, a cross member slidable in the shank with which the expanding means is connected, a sleeve reciprocable on the shank, and a nut threaded on the sleeve for vertical adjustment, said nut providing a connection between the cross member and the sleeve.

3. A tapping head for threading machines including a head having expandable chasers therein, means for expanding the chasers including a mandrel and a reciprocable sleeve with which the mandrel is connected, said sleeve having a flanged peripheral portion, and means for effecting a relative movement between the sleeve and the head, including a pair of side rods, a sleeve on each of the side rods, limiting stops on the side rods between which the sleeves are movable, and yoke members detachably connected with each of the said sleeves which slide on the side rods, said yokes each having a curvature of less than 180° and extending into the flanged periphery of the said first sleeve whereby they may be removed out of engagement with the said flanged periphery by disconnecting them with the respective sleeve elements on the side posts.

4. The combination in a tapping head for

- a threading machine having a shank portion and a head member containing a plurality of radial slots therein, chasers having recesses therein adapted to be received in said slots, a plate disposed on the end of the head portion
- 5 having spring pressed pins therein engaging the recesses in said chasers limiting the radial movement thereof, and means for expanding the chasers within said limits including a vertically reciprocable mandrel, a
- 10 cross member through which the mandrel is threaded permitting vertical adjustment of said mandrel, a sleeve reciprocably mounted around said shank portion having a threaded peripheral surface, an annular nut threaded on said sleeve and connected with said cross member for making a second vertical adjustment of said mandrel.
- 15 5. A tapping head for a threading machine having a shank portion and a head portion containing a plurality of radially adjustable chasers, a vertically reciprocable mandrel for expanding said chasers, a cross bar slidable in said shank and threadedly connected with said mandrel permitting vertical adjustment of said mandrel, a sleeve slidable on the said shank, an annular nut threaded on said sleeve and connected with said cross bar for vertically adjusting said bar and mandrel, and means for limiting the upward and downward movement of the sleeve and mandrel to expand and contract the chasers during the operation of the machine.
- 20 35 6. A tapping head for a threading machine having a shank portion and a head portion containing a plurality of radially adjustable chasers, a mandrel and a cross bar threadedly connected therewith permitting vertical adjustment of said mandrel, a sleeve slidable on the said shank, an annular nut threaded on said sleeve and connected with said cross bar for vertically adjusting said bar and mandrel and means for limiting the upward and downward movement of the sleeve and

- mandrel to expand and contract the chasers during the operation of the machine, said means comprising an extended flanged portion on said sleeve, a plurality of arcuate yokes engaging said flanged portion and supporting said sleeve, side rods having sleeve engaging stops thereon limiting the movement of the sleeve for removably interengaging the mandrel and chasers.
7. A tapping head for a threading machine comprising a head member having a shank portion, a plurality of radially adjustable chasers contained in said head member, means for radially expanding said chasers including a reciprocable sleeve on said shank portion connected therewith, means for limiting the movement of said sleeve in one direction relative to said shank portion during operation of the machine for disengaging the expanding means from the chasers, means
- for locking the sleeve to the head and means for limiting the movement of said sleeve in the opposite direction relative to said shank portion for releasing the sleeve from the head to expand the chasers.
8. A tapping head for a threading machine including a head member having a shank portion, a plurality of chasers contained in said head member, a mandrel for radially expanding said chasers, means for making accurate adjustment in the expansion of said chasers so that the tool may be used to thread blanks of varying diameters, said means comprising a cross bar slidable in said shank portion and through which the mandrel is threaded permitting vertical adjustment of the mandrel in relation to said cross bar, a sleeve slidably mounted around said shank, an annular nut threaded on said sleeve and connected to said cross bar for raising and lowering the cross bar making a second adjustment of the mandrel for controlling the expansion of the chasers and means for locking said mandrel to the cross bar.
9. A tapping head for a threading machine comprising a head member having a shank portion, a plurality of adjustable chasers in said head member, a mandrel for expanding said chasers, a sleeve having extended flanged portions slidable mounted on said shank, means connecting said mandrel with said sleeve, means for effecting relative movement between the sleeve and the shank including a pair of side rods, a sleeve on each side rod, limiting stops on each side of said rods between which said sleeves are slidable, a yoke connected with each sleeve and engaging the flanged portion on said first mentioned sleeve, and means for locking said first sleeve to said shank when the said second sleeves are engaging one set of stops and for unlocking said sleeve from said shank when engaging the other of said stops.
- In testimony whereof I have hereunto set my hand.
- PETER J. SHRUM.
